UNITED STATES PATENT OFFICE.

WILLIAM W. JACKSON, OF PHILADELPHIA, PENNSYLVANIA, ASSIGNOR TO MACKELLAR, SMITHS & JORDAN, OF SAME PLACE.

DESIGN FOR A FONT OF SCRIPT PRINTING-TYPE.

SPECIFICATION forming part of Design No. 14,340, dated October 2, 1883.

Application filed August 23, 1883. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Types, of which the following is a specification.

The nature of my design is clearly shown 10 in the accompanying typographic impression, to which reference is made; and it consists of a script letter of the running-hand character, unshaded and unornamented, as shown.

The character of the design is preserved in the lower case, the punctuation-marks, the 15 logotypes, and the numerals, as clearly shown.

Having now described my invention, I claim as new—

The design for a font of printing-type, as shown and described.

WM. W. JACKSON.

In presence of—

C. V. HUCH,
HERMAN METIUS.
